PORTABLE VENTILATING FAN

Joseph M. Barrett, East Cleveland, Ohio

Application March 23, 1932, Serial No. 600,590
Renewed December 24, 1934

1 Claim. (Cl. 230—259)

This invention has to do with the art of portable ventilating fans, and fans of well known commercial types. In its preferred embodiment it is a complete ventilating fan, including motor means, fan blades, and necessary wire connections. In addition to the foregoing, the invention consists of an unique carrying or storage case that will enclose fan and wire means when not in service.

10 The enclosure means serves several purposes, for instance; complete fan and wire enclosure means, forming a compact and dust proof case; use of part of enclosure case to form a support means; providing means whereby a complete fan unit can be readily carried in a traveling bag, and put in operation with a minimum effort.

When the fan is to be used, unlatching one or both lids allows access to the fan, both lids can be placed under the case proper and used as supports or legs to hold the center line of the fan up some distance from the object it is placed on; or the case lids can be opened up to approximately 90 degrees in which case the center line of fan will be at its minimum.

30 The motor with fan means can be installed on a base plate and the wire guard made integral with the base plate. When made up in this manner, the fan can be removed from case and placed at any convenient point, or the fan can be operated without removing it from the case.

While this invention contains combined instrumentalities, I wish it understood that I consider the aforesaid means not only combinatively novel, but in so far as I am advised, certain of the devices going to make up such means are new in less combinations than the whole, and some capable of individual use, as will more clearly appear hereinafter.

40 Fig. 1 shows front of the complete fan unit with lids or case covers 6, opened up to form a supporting stand for the case 4 and the fan unit 3. This view also shows stationary blade guard 2, integral to case 4.

45 Fig. 2 shows side view of Fig. 1 at A—A and illustrates the use of lids 6, as legs or supporting units for fan unit 3, and case 4. A method of connecting motor unit 3 to base 4 or 11 is shown by 13.

50 Fig. 3 is an enlarged sectional view of a means to lock and hold lids 6, in the position shown by Figures 1 and 2. The spring clip 7 is shown bearing on part 9. The position of clip 7 when lids 6 cover case 4 would be as at 1a.

55 Figures 4 and 5 show motor means connected

to a sub base plate 11, and with wire guard 12, integral with base plate 11. The base plate 11, is slidable into position shown in case 4b, as shown by dotted lines 4b. Guide strips 10, hold the motor in a fixed position when placed in case 4.

Fig. 6 shows the lids 6, in position when they are to be used to cover the open ends of case 4, as shown this results in a box like structure which in turn completely encloses the motor unit, 10 fan blades, blade guard and the lead in wire.

Fig. 7 is an enlarged sectional view of lid 6, in a position where it acts to close the open end of case 4. A depression 15, is shown receiving the tip 14a of part 14, this acting as a locking device.

The term "synchronous motor" will describe a motor means that is self starting; does not employ brushes or commutators and will use alternating current; the speed or revolutions being 20 some multiple of the current cycles being used, slippage excepted, and in its operation will not cause any perceptible disturbance in radio reception or disturb operation of apparatus using vacuum tubes.

The case 4 is shown as a rectangular shape, this however, can be any irregular shape, round or semi-round shape. The motor and blade guard means can be placed on a sub base as shown by Figures 4 and 5.

The hinged lids 6, can be used as supporting legs as shown in Fig. 2, or they can be opened approximately 90 degrees which would lower the center line of fan in respect to the structure it is placed on.

35 Due to the type of fan motor to be used, sufficient space will be available in case 4 to store the lead-in wire with its connector.

The lids 6, can be hinged to case 4, and a locking device similar to 7 can be used to hold 40 the lids in position when they are used as a support.

The motor with fan means can be enclosed in a case with one removable lid, in this event the motor and fan means would be removed from 45 case when operating; the case would only be used for storage.

Due to the simplicity of the complete unit, all that is required to put the unit in service is the uncovering of case structure by moving the 50 lids to a position where they can act as supports; then removing the wire from inside case and plugging wire into any convenient current supply, or the fan unit can be removed from case and placed at the desired position.

When the fan is not used, or is to be placed in storage; or is to be transported, the lead-in wire can be placed in case and covers used to close the open ends.

5 Having thus described my invention, what I claim is:

A ventilating device, comprising in combination, an electric motor, a fan driven thereby, an enclosing case therefor having a plurality of fixedly joined walls, the motor removably attached to one of said walls, a plurality of hinged

closure walls which when in a closed position serve to complete the enclosure for the motor and fan, said closure walls separately hinged to the one of the fixedly joined walls which forms the bottom of the device when the device is in a normal position, and latching means serving to secure the hinged walls at more than 90° from their closed position to form a support for the assembly.

JOSEPH M. BARRETT. 10
